UNITED STATES PATENT OFFICE.

ROBERT VANCE LANEY, OF CUMBERLAND, MARYLAND.

IMPROVED HOOK.

Specification forming part of Letters Patent No. 105,582, dated July 19, 1870.

To all whom it may concern:

Be it known that I, ROBERT VANCE LANEY, of Cumberland, in the county of Alleghany and State of Maryland, have invented certain new and useful Improvements in Hooks; and I do hereby declare that the following is a full, clear, and exact description of the same, reference being had to the accompanying drawing, and to the letters of reference marked thereon, making a part of this specification, in which—

Figure 1 is a top view. Fig. 2 is a side view. Fig. 3 is a top view of the trigger-plate and spring. Fig. 4 is a modification of my device.

The object of my invention is to furnish a hook that is cheap, durable, and free from all complicated mechanism, one that will sustain any degree of draft—as, for instance, when used to retain the tow-line of a canal-boat or the halyards used in hoisting or lowering the yards or sails of a ship.

My improved hook is also equally as well adapted to resist pressure, and therefore can advantageously be used to retain the bar or lever that supports the bottom of the Winan's hopper-car, and all that class of cars which are loaded at the top and unloaded at the bottom.

The nature of my invention consists in constructing the main or base plate or bar with an eye at one end and a hook at the other. The hooked end is so slotted as to receive the end of the hook-bar and allow of its being pivoted therein. The hook is firmly fastened and held by means of a trigger-plate and spring, which are secured and work in a slot formed in the body of the main or base plate.

The interior face of the hooked end of the base-plate as well as the hook-bar are both curved, the curvature of the former being much more positive than that of the bar, so that when the hook is fastened the draft or pressure it is called upon to resist is not equally borne, but supported chiefly by the base-plate, the hook-bar only resisting a degree of pressure or draft sufficient to elevate it when freed from the trigger-plate.

To enable others skilled in the art to make and use my invention, I will now proceed to describe its construction and operation.

A is the main or base plate or bar, and is

constructed of any suitable metal, and usually in the form shown in Fig. 2, where it will be observed that the forward section, A', of the base-plate or bar is crooked or curved. The degree of curvature in the working-hook is more positive than that shown in the drawing, being much nearer a semicircle in form, so that in its practical working, it matters not whether it retains a tow-line or a lever, it shall furnish almost the entire resistance required. This section A' terminates in a slotted head, a. This plate or bar A is cast or otherwise formed with an eye, B, which furnishes a convenient means of securing the device to the boat, car, &c. The body of the main plate or bar is provided with a slot or opening, B', and also with a vertical slot, b. This slot does not extend through the body of the hook, but is provided with a base rest or bearing, being cut only sufficiently deep to allow the upper surface of the end of the hook-arm to fall below and free the line in which moves the trigger-plate.

C is the hook bar or arm, and is constructed of the same metal as the main or base plate A. This hook-arm C is so curved as to leave a semi-oval recess on its inner face. In the slotted head a of the section A' of the main or base plate this hook-bar C is permanently secured by means of a bolt or pin, C', the same being so pivoted as to allow of its free working in its slotted bearing. The free end of this arm C, when the hook is to be used, or after the tow-line or other device which it is desired to retain or hold has been properly placed in the opening X, falls in the vertical slot b, where it is automatically caught and held by the trigger-plate D. This plate D is so pivoted at d as to allow of its free movement and play in the slot B', as clearly shown in Figs. 1 and 3.

D' is a spring, one end of which is permanently attached to the trigger-plate D, while the other end is free, having its bearing against the rear wall of the slot B'. D' is represented as a plate-spring in Fig. 3; but of course the coil or any other style of spring may be used.

Instead of the main or base plate A being recessed or slotted at B', so as to receive the trigger-plate D, these may both be dispensed with, and a device similar to that shown in Fig. 4 substituted, where e represents the forward end of the hook arm or bar C, E a metal ring

that encircles the body of the base-plate, and F a horizontal plate, permanently attached to the ring, and working in suitable bearing-plates f', being controlled by a spring, F'. This modification, it will be observed, fastens automatically precisely on the same principle as the one hereinbefore described.

The operation is as follows: When the hook is used as a draft-hook on canal-boats, it is permanently attached to the boat by means of the eye B. The trigger-plate D is drawn back, either by direct pressure or through a cord tied in the opening d'. This leaves the end e of the hook-arm C perfectly free. This arm is then elevated and the tow-line passed over it. When it falls again into the vertical slot b, the trigger-plate D is freed from pressure, and instantly, being automatically driven by the tension of the spring over the end e of the hook-arm C, securely locks the same in position. When the hook is used in connection with the hopper-car, it is attached at its side, falling to such a point as to leave the center of the oval opening on a line with the longitudinal or horizontal bar when in position to retain the bottom of the hopper, when the operation will be exactly the same as the one just described.

It will be seen that, owing to the nearly semi-circular form of the hook end A' and the semi-oval form of the hook-arm C when the latter is fastened, it matters not whether the hook A is called upon to resist the draft of the tow-line or pressure of the lever of the dumping-car, the pressure or draft is, of necessity, so

distributed that but a small portion of the same is borne by the hook-arm—no more, indeed, than what is sufficient to elevate it after the trigger-plate D is drawn back. Were this not the case, the draft or pressure, which is immense when the hook is used for the purposes designated, would be so great on the arm C, and, consequently, on the trigger D, as to require a powerful force to unfasten or unlock the hook, and which would therefore deprive the same of its chief advantages—that is, the instantaneous freeing of the line or lever when the same is desired.

I do not claim any of the distinctive mechanical features shown by J. L. Dickinson in his patent granted February 4, 1868, for a harness-hook.

Having thus fully described my invention, what I claim therein as new, and desire to secure by Letters Patent of the United States, is—

The main or base plate A of a draft-hook, when the same is provided with a slot, B', hook-arm C, trigger-plate D, spring D', eye B, and slot b, when said slot forms a bearing for the end of the hook-arm C, substantially as described, as and for the purpose specified.

In testimony whereof I have signed my name to this specification in the presence of two subscribing witnesses.

ROBERT VANCE LANEY.
